PETER S. DUFFY, OF NEW YORK, N. Y., ASSIGNOR TO THE BELL TALKING MACHINE CORPORATION, OF NEW YORK, N. Y., A CORPORATION OF NEW YORK.

BRAKE MECHANISM FOR PHONOGRAHS.

1,291,796.

Specification of Letters Patent. Patented Jan. 21, 1919.

Application filed June 9, 1916. Serial No. 102,608.

To all whom it may concern:

Be it known that I, PETER S. DUFFY, a citizen of the United States, residing at New York, in the county of New York and State of New York, have invented certain new and useful Improvements in Brake Mechanism for Phonographs, of which the following is a specification.

This invention relates to improvements in phonographs or talking machines, and more particularly to the brake mechanism thereof, the object of the invention being to provide improved means for automatically releasing and setting the brake on the movement of the tone arm in one direction or the other, and means for permitting the adjustment of the brake-setting means to different sizes of records.

A further object of the invention is the provision of improved means for manually operating the brake setting means from the outside of the phonograph cabinet.

In the drawings accompanying and forming part of this specification, Figure 1 is a perspective view of so much of a talking machine as is necessary to illustrate the improvement, part of the turntable and record being broken away; Fig. 2 is a detail perspective view of the brake mechanism, showing the brake in its set position and ready to be released; Fig. 3 is a cross sectional view of Fig. 4, but showing the brake in engagement with the flange of the turntable; and Fig. 4 is a plan view of the talking machine, showing the brake mechanism in dotted lines with the brake released from engagement with the turntable.

Similar characters of reference indicate corresponding parts in the different figures of the drawings.

The cabinet 2 is of the usual construction, having a flanged turntable 3 secured to and rotatable with an upright shaft 4 located centrally of the cabinet and operated from a motor.

The brake mechanism in the present instance consists of a base plate 5 secured to the platform 6 beneath the turntable. On the plate 5 is slidably mounted a second plate 7, having one end bent up at right angles, as at 8, and carrying a piece of fibrous material 9 adapted to engage the inside of the flange of the turntable. The opposite end of the slidable plate 7 is so shaped as

to form one member of a dog or clutch, as shown at 10, Fig. 2. In the present instance this plate is shown slotted longitudinally thereof and is retained on the base plate 5 by means of a pair of pins passing through said slot and secured in the base plate, said pins being provided with enlarged heads or disks 11, whereby the plate 7 is permitted to slide on the plate 5. One of the pins is extended on the upper side of its disk 11 to form a projection 12, to which is attached one end of a helical spring 13, the opposite end of which is connected to a pin 14 secured in the plate 7 near the clutch formed end thereof, whereby the slide plate 7 is maintained in its normal position under tension of the spring 13. A coöperating clutch member 15 is pivotally mounted by means of a headed pin 16 on the base plate 5 in position to engage the clutch member 10 on the operation of the sliding plate toward the clutch member 15.

Pivotedly mounted on a bracket 17 secured to the platform 6 is a bell-crank lever 18, one arm of which is provided at its end with an upturned finger 19 and the other arm 23 extends toward the base plate 5. A link 20, pivotally mounted on the bracket 17, preferably by means of the same pivot on which the bell-crank lever 18 is mounted, has at its opposite end a slot 21 through which the pin 14 in the sliding plate 7 projects, and a helical spring 22 connects this link 20 with the arm 23 of the bell-crank lever so that when the lever is operated the link 20 will move therewith and, through the medium of the slot and pin connection 14 and 21, the sliding plate 7 will be moved against the action of its spring so as to bring the clutch members 10 and 15 into engagement, thereby to lock the brake out of engagement with the flange of the turntable. The end of the arm 23 is held sufficiently far in advance of the link 20 to maintain the spring 22 always under tension, and this is accomplished in the present instance by means of a lug 24 shown as punched up from the link 20.

The brake-setting mechanism comprises a lever 25 connected by a pin 26 with one end of the clutch member 15, the pin 26 projecting through said clutch member into a transverse slot in the base plate 5, as shown in dotted lines 26' in Fig. 2, so as to limit

the pivotal movement of said clutch member 15. The lever 25 is also connected with the clutch member 15 by a helical spring 27, whereby the clutch member is maintained in position to engage the companion clutch member 10. Pivots connected to the link 25, at one end thereof, is a link 28 which is pivotally secured at its opposite end to a bracket or clamp 29 mounted on the platform 6. A washer 29' is located between the bracket and the end of the link 28. By means of the same pivot there is also pivotally secured, in frictional engagement with the link 28, a lever 30 provided at its free end with a trip finger 31 bent at right angles thereto.

For automatically operating the brake setting and releasing mechanism described, the tone arm 32 of the machine is provided in the present instance with a radially extending arm 33 adapted to project into the path of the trip fingers 19 and 31, whereby the arm 33 will contact with the finger 19 and operate the brake-releasing mechanism upon movement of the tone arm in one direction, as to the right, and will contact with the finger 31 and operate the brake-setting mechanism on the movement of the tone arm in the opposite direction.

The operation of the improved brake mechanism is as follows: With the parts in the position shown in Fig. 2 the brake is in its set position, that is the position it will occupy when in engagement with the turntable, the arm 33 of the tone arm being in contact with the trip finger 19 of the releasing mechanism. Upon moving the tone arm to the right so as to start the machine, the arm 33, through the medium of the trip finger 19, operates the bell-crank lever 18 and link 20, thereby releasing the brake and causing the plate 7 to slide toward the clutch member 15, and as soon as the two beveled faces of the clutch members come in contact the clutch member 10 will act as a cam to swing the clutch member 15 on its pivot until the cam face of the sliding clutch member has passed the cam face of the clutch member 15, whereupon the action of the spring 27 will cause the two clutch members to become engaged and thus hold the brake out of engagement with the turntable. As soon as the tone arm has traveled across the record and completed playing the piece, the arm 33 comes in contact with the trip finger 31 and, through the medium of the link 28, operates the lever 25 so as to pull on the rear end of the clutch member 15 thereby to swing said clutch member on its pivot and release the clutch members from engagement, whereupon, by the action of the spring 13, the sliding clutch member will be pulled backward so as to cause the brake 9 to engage the turntable and thereby stop the rotation thereof. The adjustment of the device to records of

different sizes is permitted by reason of the fact that the lever 30 is made as a separate piece from the link 28 and held in frictional contact therewith, so that this lever may be moved to the left or right as occasion may require to bring its trip finger 31 in proper position to be engaged by the arm 33 at the end of the record regardless of what the size of the record may be, the frictional contact between the lever 30 and link 28 being sufficient to maintain the parts in proper relation for operating the brake-releasing mechanism.

For permitting the operation of the brake-setting mechanism from the outside of the cabinet, I have provided the lever 25 with an extension 40 bent at an angle to the main portion of the lever, to which extension is yoked, as at 41, one end of a push rod 42, the opposite end of which extends through the front wall of the cabinet and is provided with an enlarged head 43 for manually operating the push rod and thereby setting the brake. It will thus be seen that should it be desired to interrupt the playing of a record this may be done without raising the top of the cabinet and without waiting for the arm 33 of the tone arm to automatically trip the finger 31, by merely giving the rod a slight push, whereupon the lever, through the medium of the extension 40, will operate to swing the dog 15 on its pivot in the same manner as when operated by the movement of the tone arm. This improvement, therefore, provides a brake mechanism having means adapted to be automatically and manually operated to set the brake, and automatically operative means for releasing the brake, the manually operating means being operable from the outside of the cabinet and the automatically operative brake-setting means being adjustable so as to make it equally operative with records of different diameters.

It will, of course, be understood that the details of construction and combinations of parts may be considerably varied without departing from the spirit and scope of this invention.

I claim as my invention:

1. In a phonograph the combination of a cabinet, a brake, automatically operative means for setting said brake on the movement of a part of said phonograph, automatically operative means for releasing said brake on the movement of a part of said phonograph, and means for also manually operating one of said means from the exterior of the cabinet.

2. A brake mechanism for phonographs, comprising a sliding clutch member, a pivoted clutch member, a lever connected to one of said clutch members for bringing the clutch members into engagement, a lever connecting the other of such clutch members for

throwing said members out of engagement, and means connected to one of said levers for manually operating the same.

3. A brake mechanism for phonographs, comprising a sliding clutch member, a pivoted clutch member, a lever connected to said sliding clutch member, a lever connected to said pivoted clutch member, means for automatically operating said levers and means 10 for also manually operating said clutch disengaging lever.

4. In a phonograph the combination of a sliding clutch member adapted to engage the rotary disk of a phonograph, a swinging clutch member in position to engage the sliding clutch member, a pivotally supported lever system connected with the swinging clutch member and adapted to be operated by a shiftable part of the phonograph.

20 5. In a phonograph the combination of a sliding clutch member adapted to engage the rotary disk of a phonograph, a swinging clutch member in position to engage the sliding clutch member, a pivotally supported lever system connected with the swinging clutch member and adapted to be operated by a shiftable part of the phonograph, and means connected to the swinging lever system and operative from the outside of the 25 phonograph for manually releasing said clutch members.

6. In a phonograph the combination of a sliding clutch member adapted to engage the rotary disk of a phonograph, a swinging clutch member in position to engage the sliding clutch member, a pivotally supported lever system connected with the swinging clutch member and adapted to be operated by a shiftable part of the phonograph, and 30 a push rod connected to the swinging lever system and operative from the outside of the phonograph for manually releasing said clutch members.

7. In a phonograph the combination of 45 a sliding clutch member adapted to engage the rotary disk of a phonograph, a swinging clutch member in position to engage the sliding clutch member, a pivotally supported lever system connected with the swinging clutch member and adapted to be operated by a shiftable part of the phonograph, said lever system including a pivotally connected lever adjustable to various sizes of records and having an operative portion in position 50 to be engaged by a shiftable part of the phonograph.

8. In a phonograph the combination of a sliding clutch member adapted to engage the rotary disk of a phonograph, a swinging clutch member in position to engage the sliding clutch member, a pivotally supported lever system connected with the swinging clutch member and adapted to be operated by a shiftable part of the phonograph, said 60 lever system including a pivotally connected

lever adjustable to various sizes of records and having an operative portion in position to be engaged by a shiftable part of the phonograph, and manually operative means extending to the outside of the phonograph 70 for also releasing said clutch members.

9. A phonograph having a rotary flanged disk, a brake mechanism therefor comprising a pivoted clutch member, a sliding clutch member having means for engaging the inner face of the flange of said disk, said clutch members having their clutch faces extending in a horizontal plane, means for bringing such clutch members into engagement, and means for throwing such clutch members out 75 of engagement.

10. A phonograph having a rotary disk, a brake mechanism comprising a pivoted clutch member, a sliding clutch member having means for engaging the edge of said 80 disk, automatically operative means for bringing said clutch members into engagement, and automatically operative means for throwing said clutch members out of engagement.

25 11. A brake mechanism for phonographs, comprising a sliding clutch member, a pivoted clutch member, a bell-crank lever connected to one of said clutch members for bringing the clutch members into engagement, and a lever connected to the other of said clutch members for throwing said members out of engagement.

12. A brake mechanism for phonographs, comprising a sliding clutch member, a pivoted clutch member, a bell-crank lever connected to one of said clutch members for bringing the clutch members into engagement, a lever connected to the other of said clutch members for throwing said members 100 out of engagement, and means for automatically operating said levers.

13. A brake mechanism for phonographs, comprising a sliding clutch member, a pivoted clutch member, a bell-crank lever connected to said sliding clutch member for bringing it into engagement with said pivoted clutch member, and a lever connected to said pivoted clutch member for throwing 105 said clutch members out of engagement.

14. A brake mechanism for phonographs, comprising a sliding clutch member, a pivoted clutch member, a bell-crank lever connected to said sliding clutch member for bringing it into engagement with said pivoted clutch member, a lever connected to said pivoted clutch member for throwing said clutch members out of engagement, and means for automatically operating said levers.

15. In a phonograph having a tone arm, the combination of a brake mechanism comprising a sliding clutch member, a pivoted clutch member, a bell-crank lever connected to one of said clutch members for bringing 110 120 125 130

the clutch members into engagement, a lever connected to the other of said clutch members for throwing said members out of engagement, and means for automatically operating said levers on the movement of the tone arm in opposite directions.

16. In a phonograph having a tone arm, the combination of a brake mechanism comprising a sliding clutch member, a pivoted 10 clutch member, a bell-crank lever connected to said sliding clutch member for bringing the clutch members into engagement, a lever connected to said pivoted clutch member for throwing said clutch members out of engagement, and means carried by said tone arm for automatically operating said levers on the movement of the tone arm in opposite directions.

17. A brake mechanism for phonographs, 20 comprising a sliding clutch member, a pivoted clutch member, a bell-crank lever connected to one of said clutch members for bringing the clutch members into engagement, a lever connected to the other of said 25 clutch members for throwing said members out of engagement, and means for also manually operating one of said levers.

18. A brake mechanism for phonographs, comprising a sliding clutch member, a pivoted 30 clutch member, a bell-crank lever connected to one of said clutch members for bringing the clutch members into engagement, a lever connected to the other of said clutch members for throwing said members 35 out of engagement, and a push rod connected to said last lever for manually operating the same.

19. A brake mechanism for phonographs, comprising a sliding clutch member, a pivoted 40 clutch member, a bell-crank lever connected to said sliding clutch member for bringing said clutch members into engagement, a lever connected to said pivoted clutch member for disengaging said members, and a push rod connected to said clutch-disengaging lever for manually operating the same.

20. A brake mechanism for phonographs, comprising a sliding clutch member, a pivoted 50 clutch member, a bell-crank lever connected to one of said clutch members for bringing the clutch members into engagement, a lever connected to the other of said clutch members for disengaging said members, means for automatically operating said 55 levers, and means for manually operating one of said levers.

21. A brake mechanism for phonographs, comprising a sliding clutch member, a pivoted 60 clutch member, a bell-crank lever connected to said sliding clutch member for bringing the clutch members into engagement, a lever connected to said pivoted clutch member for disengaging said members, means for automatically operating said 65 levers,

levers, and means for manually operating said clutch-disengaging lever.

22. A brake mechanism for phonographs, comprising a sliding clutch member, a pivoted 70 clutch member, a bell-crank lever connected to said sliding clutch member for bringing the clutch members into engagement, a lever connected to said pivoted clutch member for disengaging said members, means for automatically operating said 75 levers, and a push rod connected to said clutch-disengaging lever for manually operating the same.

23. In a phonograph having a tone arm, the combination of a brake mechanism comprising a sliding clutch member, a pivoted 80 clutch member, a bell-crank lever connected to one of said clutch members for bringing the clutch members into engagement, a lever connected to the other of said clutch members for disengaging said clutch members, and means for operating said levers on the movement of the tone arm in opposite directions.

24. In a phonograph having a tone arm, 85 the combination of a brake mechanism comprising a sliding clutch member, a pivoted clutch member, a bell-crank lever connected to one of said clutch members for bringing the clutch members into engagement, a lever connected to the other of said clutch members for disengaging said clutch members, and means carried by the tone arm for operating said levers on the movement of the tone arm in 90 opposite directions.

25. In a phonograph having a tone arm, the combination of a brake mechanism comprising a sliding clutch member, a pivoted 100 clutch member, a bell-crank lever connected to said sliding clutch member for bringing said clutch members into engagement, a lever connected to said pivoted clutch member for disengaging said members, and means carried by the tone arm for operating said levers on the movement of the tone arm in 105 opposite directions.

26. In a phonograph having a tone arm, the combination of a cabinet, brake mechanism comprising a sliding clutch member, a pivoted clutch member, a bell-crank lever 115 connected to said sliding clutch member for bringing said clutch members into engagement, a lever connected to said pivoted clutch member for disengaging said members, means carried by the tone arm for operating said levers on the movement of the tone arm in opposite directions, and a push rod connected to said clutch-disengaging lever for operating the same from outside of 120 the cabinet.

27. In a phonograph, the combination of a brake adapted to be maintained in operative position, a pair of clutch members adapted to maintain said brake out of operation, a lever connected to one of said clutch 125 members,

members for bringing said clutch members into engagement, a lever connected to the other of said clutch members for disengaging said members, said levers extending in the same direction from the clutch members, and means for automatically operating said levers.

28. In a phonograph having a turn table, the combination of a sliding brake member adapted to engage said turn table, a pivotally supported member adapted to coöperate therewith to hold the brake member out of engagement with the turn table, said members extending toward each other in substantial alinement, means operative by a part of the phonograph mechanism for setting the brake mechanism and thereby releasing the brake from the turn table, and means automatically operative by a part of the phonograph mechanism for releasing said brake thereby to permit it to engage the turn table, the said last two means including a pair of levers connected with and extending in substantial parallelism from the sliding brake member and the pivoted member.

29. In a phonograph having a turntable, the combination of a brake adapted to engage said turntable and having a hook-shaped portion, a hook-shaped member adapted to coöperate therewith to hold the brake out of engagement with the turntable, means automatically operative by a part of the phonograph mechanism for setting the brake mechanism and thereby releasing the brake from the turntable, means automatically operative by a part of the phonograph mechanism for releasing said brake thereby to permit it to engage the turntable, and manually operative means for also releasing the brake thereby to permit it to engage the turntable.

30. In a phonograph having a turntable, the combination of a brake adapted to engage said turntable and having a hook-shaped portion, a hook-shaped member adapted to coöperate therewith to hold the brake out of engagement with the turntable, means automatically operative by a part of the phonograph mechanism for setting the brake mechanism and thereby releasing the brake from the turntable, means automatically operative by a part of the phonograph mechanism for releasing said brake thereby to permit it to engage the turntable, manually operative means for also releasing the brake thereby to permit it to engage the turntable, and a push rod for operating said last means.

31. In a phonograph having a turntable, the combination of brake mechanism for said turntable and comprising means for

automatically setting the brake mechanism and for automatically releasing it and operative through a part of the phonograph mechanism, and means for also manually releasing said brake mechanism and operative from a point relatively remote from the turntable.

32. In a phonograph the combination of a sliding brake member having a hook formed end, a swinging member also having a hook formed end for engaging the hook of the sliding member, said hooks extending in a horizontal plane, and a lever system connected with said swinging member and in position to be operated by a shiftable part of the phonograph for releasing the hooked ends.

33. In a phonograph the combination of a sliding brake member having a hook formed end, a swinging member also having a hook formed end for engaging the hook of the sliding member, said hooks extending in a horizontal plane, and a lever system connected with said swinging member and in position to be operated by a shiftable part of the phonograph for releasing the hooked ends, said lever system including an adjustable member adjustable for various sizes of records.

34. In a phonograph the combination of a sliding brake member having a hook formed end, a swinging member also having a hook formed end for engaging the hook of the sliding member, said hooks extending in a horizontal plane, a lever system connected with said swinging member and in position to be operated by a shiftable part of the phonograph for releasing the hooked ends, and manually operative means extending to the outside of the phonograph for also releasing said hook formed members.

35. In a phonograph the combination of a pair of coöoperating members, one forming a brake for the rotating disk of the phonograph, and means for shifting the other member thereby to release the brake, said means including an adjustable member in position to be engaged by a shiftable part of the phonograph and pivotally connected to said brake releasing means and maintained in any of its adjusted positions by its frictional engagement with the means to which it is pivotally connected, whereby it may be adjusted for different sizes of records without the direct manual manipulation thereof.

Signed at New York, in the county of New York and State of New York, this 5 day of June, 1916.

PETER S. DUFFY.
